(57) **CLAIM**

The ornamental design for a rod gripper with linking member, as shown and described.

DESCRIPTION

FIG. 1 is a perspective view of a rod gripper with linking member showing my new design;

FIG. 2 is a another perspective view thereof;

FIG. 3 is a right side view thereof;

FIG. 4 is a left side view thereof;

FIG. 5 is a bottom view thereof;

FIG. 6 is a top view thereof;

FIG. 7 is an enlarged back view thereof;

FIG. 8 is an enlarged front view thereof; and,

FIG. 9 is a cross-sectional view of the right side thereof taking along line 9-9 in FIG. 8.

The broken lines immediately adjacent to the claimed areas represent the bounds of the claimed design while all other broken lines are directed to environment and are for illustrative purposes only; the broken lines form no part of the claimed design.

1 Claim, 6 Drawing Sheets*FIG. 1*

FIG. 3
